UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ATTACHING DEVICE FOR LAMP-SOCKETS, &c.

1,193,025.

Specification of Letters Patent.

Patented Aug. 1, 1916.

Application filed February 24, 1913, Serial No. 750,259. Renewed December 24, 1915. Serial No. 68,580.

To all whom it may concern:

Be it known that I, CHARLES J. KLEIN, a citizen of the United States, residing at Milwaukee, in the county of Milwaukee and 5 State of Wisconsin, have invented new and useful Improvements in Attaching Devices for Lamp-Sockets, &c., of which the following is a full, clear, concise, and exact description, reference being had to the accompanying drawing, forming a part of this 10 specification.

This invention relates to lamp sockets and similar devices, and more particularly to improved means for securing the same to 15 supports.

One of the objects of the invention is to provide an improved securing means for this purpose which operates automatically and with increasing effectiveness as the parts 20 are attached in the usual manner.

Another object is to provide a securing means which becomes effective upon partial attachment of the parts, but which thereafter permits exact rotary positioning of the 25 socket or other device, while a firm connection is maintained.

Another object of the invention is to provide improved means for this purpose capable of use with supports varying in screw- 30 thread pitch and diameter.

A further object is to provide simple and efficient means for securing lamp sockets and similar devices to their supports comprising few parts easily manufactured and producing 35 a substantial and durable structure.

Other objects and advantages will hereinafter appear.

In order to disclose the invention fully and clearly, I have illustrated several embodiments of the same in the accompanying drawings wherein,

Figure 1 is a sectional view of a lamp shell cap, a bushing carried thereby, a collar, a husk and a fixture nipple in attached relation; Fig. 2 shows the same parts separated; Fig. 3 is a top view taken on the line $x-x$ of Fig. 1, partially broken away to show the apertures in the cap; and, Figs. 4, 5 and 6 illustrate some of the possible modifications of the locking means.

Figs. 1, 2 and 3 illustrate the preferred form of structure. They show a lamp socket cap 1, having a solid tubular bushing or neck 2 of malleable material at its upper end. The term "solid bushing" in this de-

scription is used as distinguishing from a split or divided bushing and includes all forms of circumferentially continuous or unbroken attaching members. The bushing 2 is threaded interiorly to engage a threaded support and has its wall 3 preferably conically tapered outwardly. A collar 4 has an opening at its lower end of a diameter sufficient to permit the upper end of the bushing to enter therein. The collar is provided on its inner face, and preferably at points below its transverse axis, with a plurality (in this instance four) of preferably sharp-pointed knobs or projections 5. The upper end of the collar 4 is preferably provided with an opening of a diameter to clear 65 the threads of a fixture nipple but to engage any enlargement or shoulder of the fixture above the nipple. An ordinary fixture 6 is shown having a shouldered base 7 and 70 threaded nipple 8 to which the lamp socket 75 is to be attached.

The operation of the structure described is as follows: The collar 4 is preferably first placed upon the bushing 2, which is then 80 screwed on the nipple 8 of the support. As the cap and bushing are screwed home on the nipple the top of the collar 4 abuts the shoulder 7 of the support and the inwardly extending projections 5 on the collar bite 85 into and grip the sides of the tapered bushing with an increasing pressure as the parts are joined, thereby locking them against accidental separation. The threads of the bushing are thus strongly compressed, at a 90 plurality of points, against the fixture nipple, as clearly shown at points 5' in Fig. 3, without being mutilated, however, since the nipple acts as a mandrel. It will be noted that one or more of the upper interior 95 threads of the bushing engage the threads of the nipple before the projections of the encircling collar begins to bite into the tapered sides of the bushing. The top of the latter thus retains its accurate circular shape 100 and easy primary engagement with the nipple is always assured even after the bushing has been attached and detached a number of times.

A further advantage of this device is that 105 even after the parts are firmly secured together, it is always possible, due to the gradual tightening of the parts, to turn the bushing at least an additional half revolution. An absolutely exact rotary adjust- 110

ment is thus obtained which permits a variable positioning of the socket key for operating accessibility. By locating the projections 5 on opposite sides of the collar the pressure applied is substantially uniform and at spaced points about the bushing. Thus a single sized bushing may be efficiently employed with nipples of varying dimensions, since the yielding sides of the bushing will be compressed by the sharp-pointed knobs of the collar at a plurality of oppositely disposed points to form a tight fit with the nipple threads even though before attachment the diameters or screw pitches do not accurately correspond.

The connection between the lamp shell cap and the threaded bushing secured thereto, as shown in Figs. 1, 2 and 3, is especially advantageous in coöperation with the other features of the device. This connection is made by providing the lamp shell cap with a series of apertures 10 cut therein, preferably in a row, around the periphery of the cap and preferably in an oblique face thereof, as at 11. The bushing is made separately and preferably of thicker metal than the cap to permit more easily the tapering of the sides, as above mentioned. Around the lower end of the bushing is provided a notched flange 12 with tongues 13 corresponding in number and spacing to the apertures 10 in the shell cap. In assembling, the tongues 13 are inserted in the apertures 10 and clenched on the inside of the cap, as at 14, to make a secure connection between the parts. Among the advantages of this improved method of connection are increased strength and simplicity in manufacture. As the bushing when operated, tightly engages the fixture nipple, the resistance to rotation is materially increased with a consequent increased strain between the bushing and cap. By placing the apertures 10 in the cap on its oblique face an increased and strengthened bearing surface is presented for the bushing tongues, which counter-balances the increased strain. Furthermore, the bent ends of the bushing tongues on the inside of the cap are adapted to engage an operating tool, such as a screw-driver, by which the bushing may be screwed onto the support. The strain of rotation thus falls mainly on the thickened tongues, reinforced by being seated in the cap, as described, and any liability of stripping the connection of the cap and bushing is overcome.

In Figs. 1 and 2 a husk 9 is shown in dotted lines as used in connection with the device. Obviously, the husk may be used or dispensed with at will. It is here shown for the reason that its use is possible in a peculiarly efficient manner with the device described, since the parts may be assembled and adjusted without inconvenience or difficulty from a point axially in line with and

beyond the socket cap and without the application of set screws, which are often inaccessible on account of lack of space.

The modification shown in Fig. 4 may be used for attachment to a fixture pipe having no shoulder above its threaded nipple and in this form the collar 4 is provided with an inwardly extending threaded flange 15 at its upper end which screws on the nipple instead of slipping thereover. The structure and operation in other respects remain similar to that already described.

If preferred, the bushing may be made cylindrical, as shown in Fig. 5, wherein the threaded bushing 2 has cylindrical sides 16 adapted to coöperate with a collar 4 having on its inner face a plurality of downwardly tapered projecting ridges 17. When the cap is attached to the fixture in this case the tapered ridges 17 of the collar grip and bite into the wall of the bushing to compress the same at these points and thus lock the parts together.

The modification shown in Fig. 6 has a cylindrical bushing 2, similar to that of Fig. 5, but provided with a plurality of outwardly projecting knobs 18. The collar 4 is formed in this instance with an inner conical face 19 so that in operation the unyielding collar engages the knobs 18 of the yielding bushing which is compressed at these points to tightly grip the fixture nipple as the parts are joined.

It will be noted that in the forms shown in Figs. 4, 5 and 6 the cap and bushing are illustrated as constructed integrally instead of separately.

As many changes could be made in the above construction and many apparently widely different modifications of this invention could be made without departing from the spirit thereof, it is intended that all matter contained in the above description, or shown in the accompanying drawing, shall be interpreted as illustrative and not in a limiting sense.

What I claim as new and desire to secure by Letters Patent is:

1. A lamp socket cap having a circumferentially continuous threaded bushing for attachment to a cylindrical threaded support and means acting upon said bushing during its attachment to said support to tighten the former upon the latter.

2. A lamp socket cap having a circumferentially continuous threaded bushing for attachment to a threaded support and means acting to compress said bushing as it is threaded onto said support.

3. A lamp socket cap having a circumferentially continuous bushing for attachment to a support and a member engaging said bushing to compress the same upon its attachment to said support, the active face of one of said engaging elements being tapered.

4. A lamp socket cap having a threaded bushing to thread onto a support and means acting during the attachment of said bushing to indent and thereby tighten the same upon said support.
5. A casing cap having a threaded bushing to thread upon a support and a member acting upon attachment of said bushing to said support to effect contraction of a part of said bushing independently of the remainder thereof.
- 10 6. A lamp socket cap having a threaded bushing to be threaded onto a support and a member acting upon said bushing when attached to said support to contract said bushing at spaced points without effecting contraction thereof between said points.
- 15 7. In combination, a lamp socket cap having a threaded bushing, and means coöperating with the latter upon attachment thereof to a support to compress said bushing at a plurality of points spaced from each other and from the end of said bushing, whereby the symmetry of the end of the latter is preserved.
- 20 8. A lamp socket cap having a threaded bushing and means acting thereon during attachment thereof to a support to contract the same upon such support without contraction of the outer end of said bushing.
- 25 9. In a lamp socket for attachment to a threaded fixture nipple, in combination, a casing cap and means carried thereby for automatically locking the same to the fixture nipple during attachment, said means comprising interfitting annular bushing and locking members, both of the latter being circumferentially continuous and the inner member being threaded and having a yieldable wall to bind with the fixture nipple as screwed thereon.
- 30 10. In combination, a lamp socket cap having a circumferentially continuous bushing member and a member coöperable therewith and with a support to firmly secure said bushing to the support, one of said members having a tapered wall and the other having a plurality of projections to engage said wall.
- 35 45 40 50 11. In combination, a lamp socket cap provided with a yielding circumferentially continuous bushing having a conically tapered active face and an unyielding collar having a plurality of projections thereon adapted to engage and press upon said bushing.
- 55 12. In combination, a lamp socket cap provided with a solid bushing threaded interiorly, and a collar coöperating with the latter to radially compress the same at a plurality of spaced points upon attachment thereof to a support, said collar being held against longitudinal movement by the support.
- 60 13. In a device of the nature disclosed, in combination, a lamp shell cap having a plurality of apertures therein, a bushing having a flange provided with tongues, said tongues passing through said apertures and being clenched within said cap, and means adapted to hold said bushing in position upon attachment of the latter to a support.
- 70 14. In a device of the nature disclosed, in combination, a lamp shell cap having a plurality of apertures therein, and a bushing having a flange provided with tongues, said tongues being adapted to enter said apertures and be clenched therein to form notches whereby said bushing may be engaged to be rotated.
- 75 80 15. In a device of the nature disclosed, in combination, a lamp shell cap having a plurality of apertures in an oblique face thereof, and a bushing having a flange provided with tongues, said tongues being adapted to enter said apertures and be clenched therein to form notches whereby said bushing may be engaged to be rotated.
- 85 16. In combination, an exteriorly threaded member, an annular member of malleable metal threaded interiorly for screwing upon said first mentioned member, and means to radially indent the walls of said annular member at one or more spots of restricted area as the same is threaded upon said first mentioned member.
- 90 17. In combination, a support having a threaded portion, a casing cap having a bushing threaded interiorly for screwing upon the threaded portion of said support, and means to inherently press said bushing against the threads of said support at one or more points of restricted area surrounded by relatively unpressed areas as said bushing is screwed upon said support.
- 95 100 105 In witness whereof, I have hereunto subscribed my name in the presence of two witnesses.

CHARLES J. KLEIN.
